By J. C. Barnwaer, Atty.

UNITED STATES PATENT OFFICE.

WALTER E. HUENEFIELD, OF CINCINNATI, OHIO.

OIL BURNER.

1,402,425.

Specification of Letters Patent.

Patented Jan. 3, 1922.

Application filed September 20, 1919. Serial No. 325,166.

To all whom it may concern:

Be it known that I, WALTER E. HUENEFIELD, a citizen of the United States, residing at Cincinnati, Ohio, have invented a certain 5 new and useful Improvement in Oil Burners, of which the following is a full, clear, and exact description, such as will enable others skilled in the art to which it appertains to make and use the same, reference 10 being had to the accompanying drawings, forming part of this specification.

My invention relates generally to oil burners and more particularly to a device 15 in the nature of an adjustable stop for limiting the upward movement of the wick lifting mechanism of the oil burner, thereby preventing the wick from being turned too high.

The form of adjustable stop or wick limiting device herein illustrated and described 20 is particularly designed for use on the wick lifting means disclosed in the application for United States Letters Patent filed April 2, 1919, by Paul L. Dulaney on oil burners, 25 Serial Number 286,931.

The principal objects of my invention are, to provide a relatively simple stop or lifting device which is capable of being 30 easily and cheaply produced, said stop being readily adjustable upon the member to which it is applied in order to permit it to be reset or adjusted as the upper end of the wick burns away and said stop being very effective in performing its intended 35 functions.

With the foregoing and other objects in view, my invention consists in certain novel 40 features of construction and arrangement of parts, hereinafter more fully described and claimed, and illustrated in the accompanying drawings, in which—

Figure 1 is an elevational view of an oil burner with parts thereof in section and showing my improved stop or limiting device 45 positioned on a vertically moving member of the wick raising mechanism.

Figure 2 is an enlarged vertical section taken approximately on the line 2—2 of Figure 1.

Figure 3 is an enlarged horizontal section taken approximately on the line 3—3 of Figure 1.

Referring by numerals to the accompanying drawings, 10 designates the annular wick receptacle which receives the supply of oil through a supply pipe 11 the latter being

relatively fixed or stationary and positioned above the wick receptacle is the usual combustion chamber 12 that is supported upon a suitable carrying member 13.

A tubular wick 14 is arranged for vertical movement within the annular receptacle 10, said wick being supported by a suitable carrier 15, and the latter being connected to a cross bar 16. This cross bar is connected 65 to one of the legs of a vertically movable rod 17, the other leg of which extends downwardly past the supply pipe 11 and one edge thereof being provided with teeth 18 to form a rack that is engaged by the teeth 70 of a pinion 19. This pinion is provided with a rotatably mounted operating handle 20 and as the latter is manipulated, pinion 19 acts to move vertically disposed rod 17 and parts carried thereby upwardly or 75 downwardly as the case may be.

All of the parts just described are disclosed in the above-mentioned Dulaney application and form no part in my invention, although, as heretofore stated, my improved stop or limiting device is particularly designed for use in connection with 80 this form of wick raising and lowering means.

My improved stop consists of a loop 21, 85 preferably formed of metal, and of such size as to enclose and project a slight distance laterally from one side of the toothed leg of the vertically moving wick raising rod 17. The loop is preferably square or 90 rectangular when viewed in plan and passing through one end of said loop is a set screw 22, the inner end of which is adapted to bear directly against the side face of rod 17. Obviously by tightening this set screw 95 22, the loop is locked to the rod 17 and consequently moves vertically therewith. By proper manipulation of set screw 22, the loop 21 is locked in adjusted position upon the rod 17 so that when the wick is turned 100 upward with its upper edge projecting the proper distance above the face of the annular receptacle 10 the top of the stop will engage against the underside of supply pipe 11, as illustrated by dotted lines in Figure 2, 105 and thus said device will act as a stop to limit the upward movement of the wick.

As the upper end of the wick burns away, the stop or limiting device must necessarily be adjusted downwardly upon the rod 17, 110 thereby compensating for that portion of the wick that is consumed in service. Where

the stop or limiting device is formed of relatively thin metal it is desirable, though not essential, that a bearing member 23 such as a nut be secured to that portion of 5 the stop through which the set screw 22 passes, said nut providing ample bearing for the threaded portion of the set screw.

A wick lifting device of my improved construction is comparatively simple, can be 10 easily and quickly adjusted so as to limit the upward movement of the wick and said device is very efficient in use.

It will be readily understood that minor changes in the size, form and construction 15 of the various parts of my improved device can be made and substituted for those herein shown and described, without departing from the spirit of my invention the scope of which is set forth in the appended claims.

20 I claim:

1. In an oil burner, a tubular wick receptacle, an oil supply pipe positioned below and diametrically of said receptacle, a vertically sliding rack bar positioned near the 25 axis of said receptacle and forming part of

the wick raising and lowering means, and a stop element clamped to said bar and extending laterally therefrom to engage said oil pipe, as said bar moves relative thereto, to limit the movement of said means. 30

2. In an oil burner, a main horizontal burner member, a wick receptacle above same, a vertical rack bar, rectangular in cross section, forming part of a wick raising mechanism and positioned adjacent said main burner member, a rectangular loop adapted to surround said bar with one of the loop ends contacting with one side of said bar and with the opposite loop end spaced a substantial distance from said bar, and a screw threaded in the lower end of said loop and having its point engaging the opposite side of said bar, said loop and screw forming a quickly adjustable stop on said bar adapted to engage said main 40 burner member to thereby limit the upward movement of the wick raising mechanism. 45

In testimony whereof I hereunto affix my signature this 12th day of September, 1919.

WALTER E. HUENEFIELD.
